(57) **CLAIM**

The ornamental design for a container for volatilizing chemicals, as shown and described.

DESCRIPTION

FIG. 1 is a perspective view of a container for volatilizing chemicals showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view.

The broken lines shown in the drawings are for illustrative purposes and form no part of the claimed design.
